CLAIM

The ornamental design for a ceiling fan as shown and described.

DESCRIPTION

FIG. 1 is a top perspective view of a ceiling fan showing our new design.

FIG. 2 is a bottom perspective view thereof;

FIG. 3 is a top view thereof;

FIG. 4 is a bottom view thereof; and,

FIG. 5 is a side view thereof.

Portions of the ceiling fan shown in broken lines form no part of the claimed design.

1 Claim, 5 Drawing Sheets
